TOGGLE PRESS

Otto Hermann May, Schwabisch Gmund,
GermanyApplication February 28, 1949, Serial No. 78,768
In Switzerland August 24, 1948

11 Claims. (Cl. 100—70)

1

This invention relates to toggle presses. In former toggle presses, the toggles were ordinarily arranged so that the distance between the fixed and movable pins increased during the power strokes with a resulting force which was resisted by stresses in the press frame above the table or platen. This resulted in the requirement for large cross-sectional areas and over-all dimensions of the presses, which considerably increased their weights, regardless of type, but particularly in cases of C-throated presses.

It is an object of the present invention to eliminate these disadvantages by arranging the toggle system in such a manner that the movable pin is free to approach or recede from the fulcrum pin during the power stroke, so as to relieve the press frame of the disadvantageous stresses. An especially advantageous form of my new toggle system is achieved by arranging it with a comparatively long bell crank forming a part of the toggle which may also be favorably positioned to clear the throat of the press so as to obtain a compact arrangement of the toggle linkage in the press frame, whereby the size of the press unit may be reduced.

The invention accordingly comprises the elements and combinations of elements, features of construction, and arrangements of parts which will be exemplified in the structures hereinafter described, and the scope of the application of which will be indicated in the following claims.

In the following drawings, in which several of various possible embodiments of the invention are illustrated,

Fig. 1 is a vertical section taken through one form of my new press;

Fig. 2 is a skeleton diagram of the linkage employed in the Fig. 1 form of the invention shown in a retracted position of the ram;

Fig. 3 is a view similar to Fig. 2, showing an advanced position of the ram;

Fig. 4 is a perspective view showing another form of the invention; and,

Fig. 5 is a vertical section similar to Fig. 1, showing a third form of the invention.

Similar reference characters indicate corresponding parts throughout the several views of the drawings.

Referring now more particularly to Fig. 1, there is shown at numeral 1 a press frame carrying a table or platen 3 and having a guide 5 overhanging the table. The ram slide is indicated at 7. The linkage for operating the reciprocating slide 7 consists in a fulcrum pin 9 which is fixed for a given adjustment. This pin is carried in a slid-

2

ing block 11 supported in the frame 1, which may be adjusted in position by means of a spindle 13, threaded through the frame at 15 and controlled by a handwheel 17. Depending from the fulcrum pin 9 is a toggle crank arm 19, the lower end of which carries a knee joint 21. A connecting rod 23 joins the knee joint 21 with a crankpin 25 of a crank 27 which is rotary in a counter-clockwise direction. Rotation of the crank 27 oscillates the arm 19 between the limits shown in Figs. 2 and 3. The crank 27 is driven by means of a double-reduction gear train 29, 31, the usual flywheel 33 being employed on the main drive shaft.

The second link of the toggle mechanism is constituted by a bell crank 37, which has a relatively long arm 39 extending up from the knee joint 21. Its shorter arm 41 is laterally directed through openings 43 (in the frame) and 44 (in the ram slide) for connection with the ram slide 7. Thus the member 37 arches over the throat T. The outer end of the short arm 41 is connected with the ram slide 7 by means of a connecting link 45 pinned at one end to the short arm 41, as shown at 47, and at the other end to the ram slide, as shown at 49. At the juncture of its arms, the bell crank 37 is provided with a pin joint 51, connecting it with a movable floating element or slide 53 constrained to move in a vertical guide 55 in the frame 1.

Before describing the operation, it should be noted that the pin joint 51 is free to move up and down, and that any reactions from the work on the table 3 applied to the ram slide 7 tend to raise this point; but since its distance from the knee joint 21 is predetermined, as indicated by the dash line 57 (see Figs. 2 and 3), a reaction is set up along the line 57, which line may be treated as an equivalent effective second link of the toggle mechanism. Reaction from the work on the table 3 is applied at 47. Thus the toggle system proper may be assumed to consist of the short toggle arm 19, pivoted at 9, the knee joint 21, and the line 57 representing the second link 45 of the toggle.

Fig. 2 shows the crankpin 25 at its forward dead center position. The arms 19 and 57 are then at their maximum angle A. During motion from the forward to the rearward dead center (the latter shown in Fig. 3), the knee joint 21 moves backward on a circular path around the fulcrum pin 9. During this operation, the angle A between the effective arms 19 and 57 diminishes to a small amount approaching coincidence as a limit (Fig. 3). During this action, the pin 51 on

slide block 53 moves first down a slight amount, and then up. During this motion of translation of the pin 51, the bell crank 37 moves clockwise, thus causing the pin 47 to descend. At first, the downward velocity of the pin 51 acts in an additive manner to increase the downward velocity of the pin 47, and as link 39 crosses coincidence with link 19, the upward velocity of the pin 51 subtracts from the downward velocity of pin 47. Hence the available force increases over a desirable period toward the end of the stroke. The upward reaction of the work applied to pin 47 is resisted along line 57, placing compression in the link 19, which delivers its force to the frame at point 9. Thus the primary actions and reactions are taken up by the part of the frame below the table 3, it being necessary only to deal with small forces applied laterally in the upper part of the frame in order to guide the block 53, the latter being otherwise free to move up and down.

The total stroke of the pin 47 is shown at x (Fig. 3 related to Fig. 2). This stroke is considerably longer than it would be without the side-wise pivoted arrangement afforded by the bell crank 37. Moreover, the required shape of the bell crank for bringing about this advantage is itself advantageous in that it adapts itself to a convenient arrangement around and overreaching the press throat T. Adjustment of the position of the fulcrum pin 9 has its effect upon the effective velocity displacement diagram for the stroke x , and this is a convenience in adapting the press to particular requirements.

In Fig. 4 is shown another form of the invention, in which 59 indicates the frame, 61 the table or platen, 63 the guide for the ram slide 65, the latter being held to an internal threaded extension 67 by means of an adjustable nut 69. The fulcrum pin, which is pivoted in the frame as indicated at 71, forms the center of rotation for the toggle arm 73. The toggle arm is oscillated by means of a connecting rod 75 pinned thereto at 101, and pinned at 77 between crank discs 79 which are rotary in the frame in bearings (see numeral 80). At 81 is shown the flywheel on the main drive shaft 83, which through a gear train 85 drives two pinions 87 that mesh with gears 89 cut in the peripheries of the crank discs 79. At 91 is indicated the bell crank, pivoted at 93 to a movable floating element or slide 95 which is constrained to move vertically in a guide 97 in the frame 59. The long arm of the bell crank is shown at 99 and its lower end is pivoted at the knee joint to the toggle arm 73. Thus the pivoted point 102 between the bell crank 91 and the toggle arm is displaced from the pivot point 101 between the toggle arm 73 and the connecting rod 75. This reduces some complications that arise in making a three-way pin joint.

The short arm 103 of the bell crank 91 reaches through suitable slots in the frame and ram slide 65. These slots are not shown in Fig. 4 because they are analogous to similar slots already described in the case of Fig. 1. This short arm is linked to the member 67 of the ram slide 65 through pin joints 105 and link 107.

It will be understood in connection with Fig. 4 that there are two lateral components to the link 107, link 73, pivot 71, bearing 93, slide 95 and guide 97, those on the near side of the drawing being shown in full. Those on the far side are not completely shown in order not to complicate the drawing unnecessarily, and are mere dupli-

cates, as will be understood by those skilled in the art.

The operation of the invention shown in Fig. 4 is similar to that already described in connection with Fig. 1, except that the effective line of pull on pin 105 is directed toward pin 102, instead of toward pin 101. The line of tension is indicated at 109. This shortens the stroke of the ram slide 65 for a given throw of the crankpin 77 and simplifies the joint construction as above stated.

Referring to Fig. 5, there is shown another form of the invention, wherein the toggle linkage, instead of being folded back upon itself, is in an extended form. In this case the frame of the press is shown at 111, having a table or platen 113, a ram guide 115 and a ram slide 117. The fulcrum pin is shown at 119 and is carried in a slide 121 (guided with respect to the frame). This slide may be adjusted to different positions by means of a shaft 123 threaded through the frame at 125 and controlled from a handwheel 127 to vary the stroke of the ram slide. The shorter toggle arm is shown at 129 extending up toward the table, being linked at knee joint 131 to the connecting rod 133 which is pinned at 135 to the crank disc 137. The crank disc 137 is driven from the main shaft 139 through a gear train consisting of a worm-and-wheel combination 141, and a spur gear combination 143. The usual flywheel is shown at 145. By rotating the crank disc 137, the toggle arm 129 is oscillated around the fixed center 119. Above the table 113, the arrangement is as already described in connection with the other forms. The bell crank is shown at 147, having a long downward extending arm 149 connected with the knee joint 131, and having a short lateral arm 151 connected with the ram slide 117 through pin joints 152, 153 and the intermediate link 155. The short arm 151 passes through openings 157 and 159 in the frame and ram slide, respectively.

The ram slide 117 is in its uppermost position when the crankpin 135 reaches its right-hand dead center. In practice, the pin joints 119, 131 and 152 are not driven into the straight line 161, joint 131 remaining on the crank side of the line. During operation, the crank drive 137, 133 retracts the joint 131 until greatest displacement of it to the left is achieved upon reaching the opposite dead center. The pin joints 119 and 152 thus approach one another, thereby effecting a downward motion of the ram slide 117 toward the table 113, which provides the power stroke. The tension is along the line 161, which of course changes its position as the movement proceeds. This form of the invention differs somewhat from the other forms in that the greatest force is achieved during initial parts of the stroke of the ram slide, thereafter decreasing and then rising somewhat at the end of the stroke. In the forms of the invention shown in Figs. 1-4, the greatest force is achieved toward the end of the stroke. The action of the constructions of Figs. 1-4 is better for some purposes, as for example, in coining, while the action of the Fig. 5 form is better in other instances, such as, for example, cutting, shearing or punching, wherein not so great a force is required after initial shear has taken place.

In all forms of the invention, all parts of the toggle system above the table of the press float with respect to the frame, being bodily supported upon the knee joint 21 (Fig. 1), 102 (Fig. 4) or 131 (Fig. 5). This floating is allowed by the movable floating element or slide. In all cases, the

fulcrum joint 9 (Fig. 1), 74 (Fig. 4) or 119 (Fig. 5) supports the knee joint from the frame. Thus the entire toggle system, including the ram slide, floats with respect to the frame above or beyond the platen.

All forms of the invention have the advantage that the greatest forces in the frame are carried below the table 113, thus relieving the frame around the throat (whether C-shaped or otherwise) of large forces. Large forces, particularly in C-shaped throats, produce high stresses unless inordinately large amounts of metal are provided. Moreover, it is difficult to make C-shaped throats rigid enough to prevent tool misalignment, but by relieving the C-shape around the throat of large forces, the throats of the present machines may be made more rigid, though lighter in weight.

Returning to the matter of the forces involved in the frame below the table, taking Fig. 1 for an example, the downward force of the work on the table is applied to the frame. The primary reaction is upward on the fulcrum pin 9 and hence upon the frame in this region. Since these forces are approximately opposite, the problem of a designer is primarily to provide a sufficient frame section in shear below and just to the left of the table, which is a relatively simple matter to deal with.

By means of the present invention, the press may be made much lighter for equal strength and capacity. For example, for comparable presses of substantially equal capacities and stroke, the weight of press made according to the present invention is of the order of one-third of the weight of the former presses, and much more compact.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A toggle press comprising a frame having a platen and a ram slide on opposite sides of a work gap, a toggle linkage having a fulcrum located in the frame toward one side of the work gap, said toggle linkage comprising a link pivoted on said fulcrum and providing a swinging knee joint, a link having one end pivoted at said knee joint and extending past the work gap, and a pivot carried by said last-named link having a sliding connection with the frame on the ram-slide side of the work gap, said last-named link also having an operative connection with the ram slide and being in the form of a bell crank, one arm of which passes the work gap and the other arm of which arches thereover.

2. A toggle press comprising a frame having a platen, a toggle linkage having a fulcrum located in the frame in the region of the platen, said toggle linkage comprising a link pivoted on said fulcrum and providing a swinging knee joint, a ram slide located to reciprocate opposite the platen, a link having one end pivoted at said knee joint and extending past the platen, a pivot carried by said last-named link having a sliding connection with the frame, said last-named link also having an operative connection with the ram slide, and a driving linkage for oscillating said toggle linkage, said driving linkage having con-

nnections with the parts of the frame on the side of said platen opposite the ram slide.

3. A toggle press comprising a frame formed to provide an open C-shaped throat, a toggle linkage having a fulcrum located in the frame toward one side of the throat, said toggle linkage comprising a link pivoted on said fulcrum and providing a knee joint also on said one side of the throat, a ram slide located on the opposite side of the throat, a link in the general form of a bell crank having one arm pivoted at said knee joint and extending past the throat, the other arm of the bell crank overhanging the throat and having an operative connection with the ram slide, and a pivot carried by the bell crank having a sliding connection with the frame.
4. A toggle press comprising a frame formed to provide an open C-shaped throat, a toggle linkage having a fulcrum located in the frame toward one side of the throat, said toggle linkage comprising a link pivoted on said fulcrum and providing a knee joint also on said one side of the throat, a power mechanism located in the frame also on said one side of the throat and adapted to oscillate said link, a ram slide located on the opposite side of the throat, a link in the general form of a bell crank having one arm pivoted at said knee joint and extending past the throat, the other arm of the bell crank overhanging the throat and having an operative connection with the ram slide, and a pivot carried by the bell crank having a sliding connection with the frame, said pivot having a position on the bell crank intermediate its two arms, said sliding connection with the frame being on said opposite side of the throat.
5. A toggle press comprising a frame formed to provide an open C-shaped throat, a toggle linkage having a fulcrum located in the frame toward one side of the throat, said toggle linkage comprising a link pivoted on said fulcrum and providing a knee joint also on said one side of the throat, a power mechanism located in the frame also on said one side of the throat and adapted to oscillate said link, a ram slide located on the opposite side of the throat, a link in the general form of a bell crank having one arm pivoted at said knee joint and extending past the throat, the other arm of the bell crank overhanging the throat and having an operative connection with the ram slide, and a pivot carried by the bell crank having a sliding connection with the frame, said pivot having a position on the bell crank intermediate its two arms, said sliding connection with the frame being on said opposite side of the throat.
6. A toggle press comprising a frame formed to provide an open C-shaped throat including a platen, a toggle linkage having a fulcrum located in the frame toward one side of the throat, said toggle linkage comprising a link pivoted on said fulcrum and extending away from the platen and providing a knee joint also on said one side of the throat, a driving mechanism consisting of a crank and connecting rod between it and the knee joint and located on said one side of the throat, a ram slide located on the opposite side of the throat, and a link in the general form of a bell crank having one arm pivoted at said knee joint and directed so as to extend past the throat where it is provided with a pivoted slide connection with the frame, the other arm of the bell crank overhanging the throat where it is pro-

vided with an operative connection with the ram slide.

7. A toggle press comprising a frame formed to provide an open C-shaped throat including a platen, a toggle linkage having a fulcrum located in the frame toward one side of the throat, said toggle linkage comprising a link pivoted on said fulcrum and extending in a direction generally toward the platen and providing a knee joint also on said one side of the throat, a driving mechanism consisting of a crank and connecting rod between it and the knee joint and located on said one side of the throat, a ram slide located on the opposite side of the throat, and a link in the general form of a bell crank having one arm pivoted at said knee joint and directed so as to extend past the throat where it is provided with a pivoted slide connection with the frame, the other arm of the bell crank overhanging the throat where it is provided with an operative connection with the ram slide.

8. A toggle press comprising a frame formed to provide an open C-shaped throat including a platen, a toggle linkage having a fulcrum located in the frame toward one side of the throat, said toggle linkage comprising a link pivoted on said fulcrum providing a knee joint also on said one side of the throat, a driving mechanism consisting of a crank and connecting rod between it and the knee joint and located on said one side of the throat and extending away from its closed side, a ram slide located on the opposite side of the throat, and a link in the general form of a bell crank having one arm pivoted at said knee joint and directed so as to extend past the throat on its closed side where the bell crank is provided with a pivoted slide connection with the frame, the other arm of the bell crank overhanging the throat where it is provided with an operative connection with the ram slide.

9. A toggle press comprising a frame formed to provide an open C-shaped throat including a platen, a toggle linkage having a fulcrum located in the frame toward one side of the throat, said toggle linkage comprising a link pivoted on said

fulcrum providing a knee joint also on said one side of the throat, a driving mechanism consisting of a crank and connecting rod between it and another pivot joint on said link and located on said one side of the throat, a ram slide located on the opposite side of the throat, and a link in the general form of a bell crank having one arm pivoted at said knee joint and directed so as to extend past the throat where it is provided with a pivoted slide connection with the frame, the other arm of the bell crank overhanging the throat where it is provided with an operative link connection with the ram slide.

10. A toggle press comprising a frame having a platen and a ram slide on opposite sides of a work gap, a fulcrum located on the frame, an oscillating toggle arm extending from said fulcrum and providing a knee joint, a rotary crank, a connecting link between said crank and said toggle arm adapted upon rotation of the crank to oscillate said toggle arm and said knee joint, a substantially vertically movable floating element having a freely movable connection with the frame, and a toggle link pivoted to said knee joint, said toggle link having a connection with said movable element and having an additional operative connection with the ram slide.

11. Apparatus made according to claim 10, in which, considering the ram slide as vertical, the fulcrum and the knee joint are at points not higher than the top of the gap, and in which said movable element and said operative connection are located at points not lower than the bottom of the gap.

OTTO HERMANN MAY.
